AERIAL TOY

Elmer L. Zwickel, Chicago, Ill.

Application December 31, 1942, Serial No. 470,714

10 Claims. (Cl. 46—77)

The invention relates to an instructive and entertaining device and more particularly to a novel toy consisting of an organization of elements including a novelly constructed aircraft arranged and operable to simulate an air attack on ground objectives.

The device generally is concerned with the construction and organization of a game apparatus intended to afford considerable entertainment and develop a player's ability to physically react to mental impressions gained by observation.

An object of the invention is to provide an aerial toy with controlled means remotely operable to release missiles.

Another object is to provide an aerial toy with novel means to retain missiles.

Another object is to provide an aerial toy formed from sheet material scored and die-cut for easy assembly and positive interlocking at its various parts.

Another object is to provide a sheet blanked out to provide complementary aerial toy parts which, when assembled, are positively interlocked.

Another object is to provide a knock-down aerial toy formed of sheet material blanked and scored for easy assembly and which is substantially rigid.

Another object is to provide a game including a playing field or target and an associated aerial toy movable into a selective position for discharging missiles thereby.

Another object is to provide an aerial game consisting of a plurality of readily assembled parts which may be easily and quickly disassembled and stored as a compact unit.

The foregoing and such other objects of the invention as will appear hereinafter as the description proceeds will be more readily understood from a perusal of the following specification, in which reference is made to the accompanying drawings; wherein:

Fig. 1 is perspective view of the improved game, showing it set up and in use.

Fig. 2 is a longitudinal central sectional view through the fuselage of the aircraft forming a part of a device.

Fig. 3 is a vertical transverse sectional view taken on line 3—3 of Fig. 2.

Fig. 4 is an inverted plane view of a portion of the fuselage showing parts of the bottom wall broken away to better illustrate its construction; taken on line 4—4 of Fig. 2.

Fig. 5 is vertical sectional view of the missile container, taken on line 5—5 of Fig. 2.

Fig. 6 is a plan view of the blank from which the fuselage is formed.

Fig. 7 is a plan view of the wing blank.

Fig. 8 is a plan view of the stabilizer blank.

Fig. 9 is an enlarged detailed sectional view of the flap and tab interlock used for joining various parts of the fuselage.

Fig. 10 is a detail of a pulley construction.

Fig. 11 is a detail of a pulley part.

The invention is concerned primarily with the construction and functions of the aircraft 11 best illustrated in Figs. 1 and 2, which may be used independently of the other parts of the complete game apparatus. As best shown in Fig. 1, the game may include a playing field or target area 12 printed or otherwise provided, preferably on the inside face of the bottom 13 of a box or other container in which the apparatus is enclosed when not in use. The playing field or target-area may include various objects 14 printed thereon or, if desired, movable objects 15, such as ships, buildings, tanks, etc. may be selectively arranged thereon.

In assembling the game apparatus, the box portion 13 is positioned end to end with the box top 16, as shown, and suitable uprights 17 are inserted, one in each outside end wall of each box portion. These uprights may be of one piece but it is preferred that they be provided in two or more sections as shown so as to readily fit within the box when disassembled. Any accepted structure may be employed in providing these uprights such as for example the tubular telescoping structure illustrated. In the operation of the instance apparatus it is necessary that one of the uprights extend higher than the other so that a trolley 18 connected at its ends to the upper ends of said uprights will be inclined downwardly towards the box portion having the target-area therein.

It will become evident however, that other means than that illustrated may be utilized to support a trolley in an inclined position above a playing field or any other object which it is desired to use as a target. For example, the opposed ends of the trolley can be attached readily to suitably positioned chairs or other articles of furniture or the like which may be available.

The trolley 18 is adapted to support a toy aircraft, such as, for example, the airplane 19 illustrated, in a manner to permit said aircraft to gravitate along the inclined trolley into a position

tion over and above the target area 12. At any time during the travel of said aircraft along said trolley the player may, in a manner to be better understood as the description proceeds, actuate means within the aircraft to release suitable missiles 21 therefrom which gravitate freely towards the target-area.

Referring now to the specific construction of a selected form of aircraft 19, the body or fuselage 22 thereof preferably is formed from a suitable piece of sheet material such as cardboard, pressboard, fibre-board, heavy paper or the like, which is die-cut for ready separation (punch-out) from a larger sheet and suitably scored and slotted to facilitate an interlocking of certain portions upon being properly folded into the desired shape. As best illustrated in Fig. 6, the fuselage 22 consists of a top wall 23, side walls 24, and a bottom wall 25, all preferably interconnected at their tail portions along scored lines 26 and having complementary slotted flaps 27 and tabs 28 at their free forward end portions. When the sheet is folded along the scored lines 26 to provide an elongated body or fuselage, preferably tapering at each end, the complementary tabs 28 and flap 27, and tabs 29 and flaps 31 on the complementary edges of the tail portion, are interlocked. The forward or nose portion of the fuselage may be suitably closed by overlapping flaps 32 having complementary interlocking tabs 33 and slots 34 as shown.

A wing portion 35, best shown in Fig. 7, also is formed from a piece of sheet material and is adapted to be fitted transversely through aligned slotted openings provided in the fuselage at the junctures of the top wall with the side walls, as at 36. Inadvertent shifting of the wing is prevented by providing thereon partially severed portions 37 which are folded upwardly against the opposite edges of the fuselage top wall 23 after the wing is in place. These portions 37 constitute spaced hanger arms between which a suitable roller 38 or other nonfriction element is journaled and by means of which the aircraft is suspended for free movement along the trolley 18.

The wing 35 also has a flap 39 on its leading edge of a length slightly greater than the width of the top wall. As best shown in Figs. 2 and 3 this flap is folded downwardly at an incline to interlock with inclined slots 40, one provided in the upper edge of each fuselage side wall 24. A tab 41 is also provided in the fuselage top wall 23 for interlocking engagement with a slot 42 centrally located on the leading edge of said wing. It should be apparent that the wing 35 is securely interlocked with the fuselage side walls and that the top wall 23 is interlocked with the wing, thereby providing a rigid adequately reinforced structure for withstanding any strain imposed thereon while suspended.

The stabilizer 43 illustrated in Fig. 8 preferably has parallel slots 44 extending inwardly from one edge for interlocking engagement with the fuselage side walls 24 when the former is mounted in place. If desired, a rudder 45, best illustrated in Fig. 2, may be mounted on the rear end of the fuselage top wall and a propeller 46 may be affixed to the fuselage nose in any suitable manner, such as for example, by a pin forced through the four material thicknesses covering the nose end.

Inadvertent withdrawal of the various tabs 28, 29 and 33 from their complementary slots may be prevented by providing each tab with a

suitable lip 50 which tends to move out of the plane of its tab after the latter is inserted through its slot.

The fuselage 22 is provided with a suitable receptacle or container 47 within which one or more missiles 21 are adapted to be placed. This receptacle may best be formed by cutting a suitable flap 48 in the fuselage top wall and bending said flap downwardly at an incline into the body thereof during assembly. The flap 48 is retained in such folded down position by interlocking engagement of tabs 49, provided on its opposed edges, with suitable slots 51 in the fuselage side walls. The cutting and dislocation of the flap leaves an opening in the fuselage top wall through which the missiles are loaded. The fuselage bottom wall 25 is similarly provided with a flap 52 having like tabs 53 on its opposed edges which interlock with slots 54 in the fuselage side walls to retain said flap in an upwardly inclined position. As best shown in Fig. 2, the top wall flap 48 terminates short of the fuselage bottom wall thereby leaving a space 55 for reception of a closure 56 for the bottom wall opening.

The closure 56 also is formed of sheet material and as shown in Fig. 4, it is substantially tapered lengthwise to conform to the fuselage tail contour and terminates in a narrow extension 57 which projects rearwardly of the tail portion. The forward or enlarged end of the closure member has transversely extending opposed tabs 58 each of which extends through one of a pair of guide openings 59 provided in the fuselage side walls. The closure member 56 normally is positioned as illustrated in Fig. 2 so as to close the fuselage bottom wall opening to retain the missiles 21 in the receptacle. Movement of the closure member 56 is effected manually by remote control by means of a cord 61 or other flexible element which is always maintained within easy reach of the player.

In use, the aircraft is positioned and held at the highest end of the trolley 18 with the control cord 61 hanging slack and the closure 56 in its closed position. The aircraft is then released and it gravitates downwardly along the trolley. Its rate of travel can be increased or decreased by increasing or decreasing the degree of trolley incline. This movement carries the aircraft over the target area and, at any time believed to be opportune by the player, the closure control cord 61 is tensioned momentarily. This draws the closure 56 rearwardly the length of the guide openings 59 and the missile or missiles are freed and drop from the fuselage onto the target area. The aircraft is then returned to the high end of the trolley and reloaded. In order to facilitate recording of hits upon any specified target area or other object, the missiles 21 may be provided with a piercing element, such as for example, a needle point 62, so as to be retained at the point of impact until manually removed.

It should be evident that a very entertaining organization is provided wherein two or more players may cooperate to the extent of each operating the device a predetermined number of times and recording the number or value of hits in predetermined target areas. The device also tends to develop the ability of the player to co-ordinate physical re-action with observation. In other words, a player may become quite skilled in observing the precise position required by the aircraft to cause the missiles to hit a predetermined target area and responding instantane-

ously by tensioning the cord to discharge the missiles at the intended place.

While a conventional pulley 38 has been illustrated in the assembly views herein as preferred, the built-up punch-out pulley illustrated in Figs. 10 and 11 may be provided. As there illustrated the pulley includes a hub 63 formed of a rolled sheet, having tabs 64 at its ends insertable in slots 65 in the pulley flanges or disks 66. A pin 67 pierces the centers of the discs for mounting the pulley on the hanger arms 37. Catching of the trolley 18 in the slit at the joining of the hub to the disks is avoided by providing washers 68 at the hub ends.

Although an exemplary form of apparatus has been illustrated herein it should be understood that the organization as a whole is capable of incorporating a variety of modifications and that the aircraft illustrated in detail may embody variations from the shape and precise structure shown providing such device includes means to retain and instantaneously release missiles upon elective operation without departing from the spirit of the invention or the scope of the appended claims.

I claim:

1. A toy aircraft including an elongated body having top, bottom and side walls, hangers on said top wall adapted to be engaged with an elevated trolley whereby the aircraft can move substantially horizontally, a flap formed in the top wall to define an opening when said flap is folded downwardly into said body, a flap in the bottom wall to define an aligned opening when said flap is folded upwardly into said body, means securing said flaps in such folded position to provide spaced front and rear walls of a receptacle having as its sides the side walls of said body, a movable closure for the bottom wall opening whereby at least one missile may be retained in said receptacle, and means operable to move the closure to discharge the missile.

2. A toy aircraft including a hollow body having a top wall, a bottom wall and connecting side walls, a flap partially severed from said top wall, a flap partially severed from said bottom wall, said flaps being in substantially vertical alignment and being folded each along an unsevered edge into the space between said side walls, said flaps and portions of the side walls defining a missile chamber, an obstruction for the bottom wall opening whereby a missile is retained in said chamber, and control means connected to said obstruction operative to move it from a closed into an open position to discharge the missile.

3. A toy aircraft including a body formed from sheet material folded to define a top wall, a bottom wall and connecting side walls, a sheet material wing portion insertable beneath the top wall through slotted openings at the junctures of said wall with the respective side walls, a flap on the leading edge of said wing portion, and said side walls each having an angularly disposed slot communicating with the respective slotted openings both to receive said flap when the wing portion is in place to reinforce the wing against flexing longitudinally and prevent its movement upwardly away from its contact with the side walls.

4. A toy aircraft including a hollow body having a top wall, a bottom wall and connecting side walls, a flap partially severed from said top wall,

5 a flap partially severed from said bottom wall, said flaps being in substantially vertical alignment and being folded each along an unsevered edge into the space between said side walls, said flaps defining front and rear walls of a missile chamber, an obstruction for the bottom wall opening whereby a missile is retained in said chamber, and control means connected to said obstruction operative to move it from a closed into an open position to discharge the missile.

5. A toy aircraft including an elongated body having top, bottom and side walls, hangers on said top wall adapted to be engaged with an elevated trolley whereby the aircraft can move substantially horizontally, a flap formed in the top wall to define an opening when said flap is folded downwardly into said body, a flap in the bottom wall to define an aligned opening when said flap is folded upwardly into said body, means securing 15 said flaps in such folded position to provide spaced front and rear walls of a receptacle within said body, a movable closure for the bottom wall opening whereby at least one missile may be retained in said receptacle, and means operable to move the closure to discharge the missile.

6. A toy aircraft including a hollow body having a top wall, a bottom wall and connecting side walls, spaced partitions in said body to define with said side walls a missile receptacle, at least one of said partitions being inclined, said top and bottom walls having openings communicating with said receptacle, a longitudinally slidable closure for the bottom wall opening, and means operable to move said closure.

30 7. A one-piece fuselage for a toy aircraft comprising a top wall, two side walls and a bottom wall, the top and bottom walls having openings therein defined by partially severed flap portions, said flap portions being foldable into the fuselage 20 to define front and rear walls of a receptacle.

8. A toy aircraft including a hollow body having a top wall, a bottom wall and connecting side walls, said top wall having an opening, a flap partially severed from the bottom wall, said flap being 45 in substantial alignment with the top wall opening and foldable upwardly between the side walls, said flap defining an end wall of a receptacle having as its side walls the side walls of the body, and a movable closure for the opening formed in the 50 bottom wall upon folding the flap.

9. A fuselage for a toy aircraft formed of a blank folded and interlocked to provide a bottom wall, side walls and a top wall joined along complementary edges by folds, said top and bottom 55 walls each having an opening, at least one edge of the top opening being out of vertical alignment with the complementary end edge of the bottom opening, and an inclined transverse partition wall in said fuselage having its top and bottom edges in substantial registry with the said end edges 60 respectively of said wall openings.

10. A fuselage for a toy aircraft formed of a blank folded and interlocked to provide a bottom wall, side walls and a top wall joined along complementary edges by folds, and flaps partially 65 severed one from the top wall and one from the bottom wall foldable into a position between the side walls when the fuselage is formed, the folding of said flaps defining a top and bottom wall opening.

ELMER L. ZWICKEL.
